REFRIGERATING APPARATUS

Henry Wiggers, Chandler, Ind., assignor, by
mesne assignments, to Reconstruction Finance
Corporation, Chicago, Ill., a corporation

Application August 22, 1933, Serial No. 686,298

13 Claims. (Cl. 62—108.5)

My invention relates to refrigerating apparatus of the mechanical or gas type intended for household, domestic or similar uses, in which freezing trays for making ice cubes or freezing food products such as desserts and the like are supported on or housed within an evaporating or freezing chamber, and has particular reference to a device for imparting an initial upward movement to the tray to break the ice seal or bond existing between the freezing tray and its supporting structure.

It is a well recognized fact among those familiar with the operation of mechanical and gas refrigerators that during the freezing process, a layer or coating of ice frequently forms on the surface of the evaporator shelf or structure and on the surfaces of the tray, and that when it is attempted to remove the tray from the evaporator, this ice layer or coating forms a seal or bond which renders it extremely difficult to remove the tray. This condition is especially noticeable when the freezing trays are permitted to remain within the evaporator during relatively long periods and/or when the evaporator needs defrosting to melt away the thick layer or coating of ice which has accumulated thereon. When such a condition exists, it is necessary to either exert a powerful upward and outward pressure on the exposed handle of the tray, which pressure, due to the relatively thin construction of the tray and handle, frequently results in the breaking off of the handle or the bending of the tray, or to resort to the use of a knife, screw-driver or other similar tool, which tool is inserted between the tray and evaporator and is utilized to pry the tray upwardly or to otherwise break the adhering seal or bond existing between the tray and evaporator, this latter procedure being unsatisfactory and time-consuming and frequently resulting in irreparable damage or injury to the tray or to the evaporator.

The condition above referred to has been recognized, and various mechanical means have been associated with the tray or with the evaporator to impart an initial tilting or lifting movement to the tray to break the ice seal or bond prior to the manual withdrawal movement of the tray from the evaporator. However, such devices are ordinarily quite complicated, require a rather complete modification of the tray structure and/or evaporator, and, because of their complicated construction and operation, have not proven successful or practical.

It is an object of my invention to provide a novel device for association with a freezing tray or evaporator which will impart an initial tilting or

lifting movement to the tray to break the ice seal or bond existing between the tray and evaporator, which device is simple in construction, cheap and easy to manufacture, strong and durable, and highly efficient in the purpose for which designed. 5

It is a further object of my invention to provide a rotary cam member mounted on, or adapted to cooperate with, the ice cube tray or the evaporator, and so constructed that upon partial rotation, the cam member will directly and positively lift or force the tray from its adhering contact with the evaporator to permit ready removal of the tray when it is desired to obtain access to the contents thereof. The cam member may be permanently mounted on each tray or on each evaporator shelf or, if desired, may consist of a separate tool member having a cam surface or surfaces which can be selectively brought into engagement with a portion of each tray, and which on partial rotation, will impart the necessary initial tilting or lifting movement to break the seal or bond existing between each tray and the evaporator shelf. 20

It is a still further object of my invention to provide a novel ice cube tray having a rotary cam member mounted on, or adapted to cooperate with, the base of the ice cube tray, and to so construct and position the cam member that its bottom surface normally lies flush with the bottom surface of the tray to permit intimate contact between the tray and evaporator during freezing, and which cam, upon partial rotation, will extend below the surface of the tray and bear upon the underlying surface of the evaporator to lift the forward end of the tray upwardly a sufficient distance to thus break the ice seal or bond existing between the tray and the evaporator. 30 35

In the accompanying drawing forming a part of this specification:

Figure 1 is a fragmentary front elevation of an evaporator unit of conventional design, showing an ice cube tray in which a preferred form of my invention is embodied, said tray being mounted in one of the freezing compartments of the evaporator unit. 40 45

Fig. 2 is an inverted plan view of an ice cube tray equipped with a preferred form of my improved tray lifting device.

Fig. 3 is a fragmentary side elevation, partly in section, of an ice cube tray equipped with a preferred form of my improved tray lifting device, showing the tray resting upon its supporting evaporator shelf. 50

Fig. 4 is a perspective, disassembled view of the 55

details of a preferred form of my tray lifting device.

Fig. 5 is a plan view of a preferred form of my tray lifting device.

Fig. 6 is an enlarged sectional view through the forward end of the tray and through a preferred form of my tray lifting device, showing the relation of parts when the lifting device has been actuated to effect an initial lifting movement of the tray preparatory to the tray's withdrawal from the evaporator unit, and,

Fig. 7 is a view similar to Fig. 3 and showing the wall defining the top of the depression inclined downwardly from the front of the depression toward the rear thereof to form an inclined cam surface, and

Fig. 8 is a view similar to Fig. 6 but showing a modified form of my invention in which the wall defining the top of the depression is inclined from the left side of the depression downwardly toward the right side thereof to form an inclined cam surface which will cooperate with the inclined cam surface of the interposed cam to produce a double cam lifting action.

Referring more specifically to the drawing, wherein like reference characters have been employed to designate like parts throughout the several views, the numeral 1 designates an evaporator unit of a mechanical or gas refrigerator of any conventional or preferred construction, which unit includes spaced shelves 2 defining a plurality of separate freezing compartments 3, each adapted to receive and house an ice cube tray 4, the bottom surface of which is in intimate contact with the supporting shelf to effect the desired freezing of the contents of the tray. To assist in the sliding insertion and withdrawal of the trays 4 into and out of the freezing compartments 3, each tray may, if desired, be provided with a handle 5 riveted or otherwise secured to the downwardly-extending front flange 6 of the tray.

The bottom surface of the preferred form of my improved ice cube tray is provided with a shallow depression 7 substantially semicircular in plan and extending to the forward edge of the tray at about the mid-portion thereof. The top wall of the depression 7 is perforated to receive therein a vertically extending stud 8, the upper end of which is then hammered or otherwise headed to rigidly secure the stud to the top wall of the depression. The stud 8 is provided intermediate its ends with an enlarged central portion 9 perforated at 10 to receive the inturned end 11 of a coiled torsion spring 12 adapted to surround the enlarged portion 9 for a purpose to be hereinafter described. The stud 8 may terminate in a reduced threaded portion 13 adapted for threaded engagement by a nut 14, or, if desired, a washer may be placed on the end of the stud 8, and said end peened or riveted to retain the washer on the end of said stud.

The tray lifting cam of my present invention comprises a member 15 made of hard rubber, bakelite or other material, this member being substantially circular in plan, perforated at its center, as at 16, and provided with a radially-extending operating handle 17. The upper face of the member 15 is provided with an upstanding, inclined marginal flange 18, which flange gradually increases in height from a minimum at 19 to a maximum at 20, this flange constituting, in effect, an inclined plane or wedge. The flange 18 is perforated at 21 to receive the straight end 22 of the coiled torsion spring 12.

When assembling the tray lifting mechanism on the stud 8, the coiled torsion spring 12 is placed around the enlarged portion 9 of the said stud and the inturned end 11 of said spring is inserted within the perforation 10. The straight end 22 of the spring is then inserted within the hole 21 in the flange 18 and the lifting cam 15 placed on the stud with the inclined flange 18 extending upwardly. The nut 14 then is screwed onto the threaded portion 13 of the stud to retain the several parts in assembled position, or, if desired, the end of the stud 8 may be left unthreaded and a washer placed over the said end, which end can be peened or riveted to rigidly retain said washer on the stud. When so assembled, the torsion spring 12 will exert its force to retain the operating handle 17 in a normal position adjacent the right side of the forward end wall of the tray, as viewed in Fig. 1 of the accompanying drawing, and when the handle is so positioned, the high portion 20 of the inclined flange 18 is disposed beyond the forward end wall of the tray and the bottom surface of the cam member 15 lies flush with the bottom surface of the tray and, hence, the tray can be filled and inserted within the freezing compartment 2 with the tray bottom resting throughout its length in direct contact with the tray-supporting shelf 2.

From the above explanation and description of the construction of my present invention, it will be obvious that when it is desired to remove the ice cube tray 4 from the freezing compartment 3 of the evaporator unit, the operator grasps the handle portion 17 of the tray lifting device and moves said handle from its normal position at the right side of the tray toward a position at the left side thereof. The initial rotation of the member 15 will force the high portion 20 of the inclined flange 18 beneath the underside of the top wall of the depression 7 and cause the member 15 to move downwardly on the stud 8 and into contact with the top surface of the underlying supporting shelf 2. Continued rotation of the member 15 toward the left will interpose the high portion 20 of the inclined flange between the shelf 2 and the underside of the top wall of the depression 7 and, due to the inclined plane or wedge action occasioned by the flange 18, the ice cube tray will be lifted at its forward end as indicated in dotted lines in Fig. 3 of the accompanying drawing and the ice seal or bond which existed between the tray and shelf will be completely broken. Upon release of the handle 17, the coiled torsion spring 12 will return the handle 17 to its normal position and the tray may then be readily removed from the compartment 3 by grasping the handle 5 and pulling the said tray outwardly of the evaporator unit.

While I have elected to illustrate and describe my invention as applied directly to an ice cube tray, it is to be understood that the tray lifting mechanism herein shown and described may, if desired, be mounted within a depression in the evaporator shelf located beneath the forward end of the ice cube tray with the cam portion extending downwardly and the operating handle exposed for manual manipulation. It is to be further understood that the top wall of the depression in the tray or the bottom wall of the depression in the evaporator shelf, instead of being plane as above described, may be provided with an inclined cam surface which will cooperate with the inclined cam surface of the interposed cam to produce a double cam lifting action. By way of illustration, I have shown in Figs. 7

and 8 of the accompanying drawing a slightly modified construction in which the top wall 23 defining the top of the depression is inclined downwardly from left to right and from front to rear, this inclination providing an inclined cam surface which will cooperate with the inclined cam surface of the interposed cam to produce the double cam lifting action. Further, instead of permanently securing the cam to the tray or shelf, I may provide the depression in the tray or shelf with a centrally-positioned stud, and use a separate tool having a hook-shaped end the hooked portion of which is provided with an upper and/or lower cam surface, and by hooking 15 such a tool around the said stud and moving the tool in a clockwise or counterclockwise direction depending upon whether the hooked end is engaged at the left or right side of the stud, the said cam surface, will cooperate with the plane 20 or inclined surface of the depression to force the tray away from the evaporator shelf. It is to be further understood that the forms of my invention herein shown and described are to be taken as preferred embodiments of the same and that 25 various changes may be made in the shape, size and arrangement of parts without departing from the spirit of my invention or the scope of the subjoined claims.

Having thus described my invention, I claim:

30 1. A refrigerating apparatus including an evaporating shelf, an ice cube tray removably supported on said shelf, and means positioned in a depression between said shelf and tray to break the adhering ice-seal or bond existing between 35 said shelf and tray, said depression having an inclined cam surface, said means comprising a rotary cam within the depression and normally flush with the walls defining said depression and having an inclined cam surface to coat with the 40 inclined cam surface in the depression, and means to rotate the said cam to force the two inclined cam surfaces together to force the tray out of contact with said shelf.

2. A refrigerating apparatus including an 45 evaporator shelf, an ice cube tray removably supported on said shelf, and means between the shelf and tray to break the adhering ice-seal or bond existing therebetween, said means comprising a horizontal, rotary lifting cam having an inclined cam surface, said cam being normally flush with the contacting surfaces of the shelf and tray, and means for rotating said cam about a vertical axis to cause the cam to force the tray out of contact with said shelf.

50 3. A refrigerating apparatus including an evaporator shelf, an ice cube tray removably supported on said shelf, and means positioned in a depression between said shelf and tray to break the adhering ice-seal or bond existing between 55 said shelf and tray, said means comprising a horizontal, rotary lifting cam having an inclined cam surface, said cam being positioned within said depression and being normally flush with the walls defining said depression, and means for 60 rotating said cam about a vertical axis to cause the cam to extend outwardly beyond the walls defining the depression to force the tray out of contact with said shelf.

4. A refrigerating apparatus including an 70 evaporator shelf, an ice cube tray removably supported on said shelf, and means positioned in a depression between said shelf and tray to break the adhering ice-seal or bond existing between 75 said shelf and tray, said means comprising a stud positioned vertically within the depression, a

horizontally-positioned cam mounted for rotation about said vertical stud and having an inclined cam surface, said cam being normally flush with the contacting surfaces of the shelf and tray, and means for rotating said cam about the vertical stud to force the tray out of contact with 5 said shelf.

5. A refrigerating apparatus including an evaporator shelf, an ice cube tray removably supported on said shelf, and means positioned between the shelf and tray to break the adhering ice-seal or bond existing therebetween, said means comprising a vertical stud, a horizontal, rotary cam mounted on the stud and having an inclined cam surface including a high portion, a spring 10 acting on the cam member to normally retain the high portion of the inclined cam surface out of engagement with the shelf or tray, and means for rotating said cam about the stud in opposition to said spring to force the high portion of 15 the inclined cam surface between the shelf and tray to force the tray out of contact with said shelf.

6. A refrigerating apparatus including an evaporating shelf, an ice cube tray removably supported on said shelf, and means positioned in a depression between said shelf and tray to break the adhering ice-seal or bond existing between 20 said shelf and tray, said means comprising a vertical stud mounted in the depression, a horizontal cam adapted for rotation around said stud and having a high portion, a torsion spring having one end anchored to the stud and the other end anchored to the cam to normally retain the cam within the walls defining the depression with 25 the high portion of the cam out of contact with the shelf or tray, and an operating handle for rotating said cam around the stud in opposition to said torsion spring to force the high portion 30 of the cam between the shelf and tray to force 35 the tray out of contact with said shelf.

7. A container for use in a cooling device such as a refrigerator evaporator, and manually shiftable means pivoted on a vertical axis to the bottom of the container in position to engage a container supporting portion of an evaporator in which the tray may be mounted over a substantial area, said manually shiftable means being adapted when shifted to apply a force between 45 said container supporting portion and said container in a direction to separate the bottom of the container from said portion whereby to break 50 an ice bond therebetween.

8. An ice cube tray having a depression in the bottom thereof extending to a side wall of the tray, a cam positioned in said depression with the bottom surface normally flush with the bottom surface of the tray and with the high portion of the cam normally extending out of the depression and beyond the side wall of the tray, and means for moving said cam to cause the 55 bottom surface of the cam to extend below the bottom of the tray.

9. An ice cube tray having a depression in the bottom thereof extending to a side wall of the tray, a rotary cam positioned in said depression with its bottom surface normally flush with the bottom surface of the tray and with the high portion of the cam normally extending out of the depression and beyond the side wall of the tray, and an operating handle for the cam for 60 rotating the same to force the high portion of the cam into contact with the wall defining the top of the depression to cause the bottom sur- 65

face of the cam to extend below the bottom of the tray.

10. An ice cube tray having a depression in the bottom thereof extending to a side wall of the tray, a downwardly-extending stud secured to the bottom of the tray and extending into said depression, a horizontal, rotary cam having an inclined cam surface mounted on said stud with the bottom surface of the cam normally flush with the bottom surface of the tray and with the high portion of the inclined cam surface normally extending out of the depression and beyond the side wall of the tray, a spring member for retaining said cam in its normal position, and means for rotating the cam around the stud in opposition to said spring to force the high portion of the inclined cam surface into contact with the wall defining the top of the depression to cause the cam to move axially of the stud 10 and to extend the bottom surface of the cam below the bottom of the tray.
11. An ice cube tray having a depression in the bottom thereof extending to a side wall of the tray, a downwardly-extending stud secured to the bottom of the tray and extending into said depression, a horizontal, rotary cam mounted on the stud and having an upstanding inclined marginal flange constituting a cam surface, the bottom surface of the cam being normally flush with the bottom surface of the tray and the high portion of the inclined cam surface normally extending out of the depression and beyond the side wall of the tray, a torsion spring having one end anchored to the stud and its other end anchored to the cam to retain said cam in its normal position, and a handle portion formed integrally with the cam and extending beyond

the side wall of the tray for rotating the cam around the stud in opposition to the torsion spring to force the high portion of the inclined cam surface into contact with the wall defining the top of the depression to cause the cam to move axially of the stud to extend the bottom surface of the cam below the bottom of the tray.

12. A refrigerating apparatus including an evaporator shelf, an ice cube tray removably supported on said shelf, and means between the shelf and tray to break the adhering ice seal or bond existing therebetween, said means comprising an inclined cam surface positioned between the shelf and tray, a rotary lifting cam normally flush with the contacting surfaces of the shelf and tray and having an inclined cam surface to cooperate with the inclined cam surface between the shelf and tray, and means for rotating the cam to force the cooperating inclined cam surfaces together to force the tray 20 out of contact with said shelf.

13. An ice cube tray having a depression in the bottom thereof extending to a side wall of the tray, the top wall defining said depression being inclined to form an inclined cam surface; a cam having an inclined cam surface to cooperate with the inclined cam surface of the wall of the depression, said cam positioned in said depression with the bottom surface of said cam normally flush with the bottom surface of the tray and 30 with the high portion of the cam normally extending out of the depression and beyond the side wall of the tray, and means for moving said cam to move the cooperating inclined cam surfaces into engagement to cause the bottom surface of 35 the cam to extend below the bottom of the tray.

HENRY WIGGERS.
